UNITED STATES PATENT OFFICE.

CARL O. FIRST, OF MEADVILLE, PENNSYLVANIA.

CAR-FENDER.

1,383,196.

Specification of Letters Patent. Patented June 28, 1921.

Application filed September 30, 1920. Serial No. 413,701.

To all whom it may concern:

Be it known that I, CARL O. FIRST, a citizen of the United States, residing at Meadville, in the county of Crawford and State 5 of Pennsylvania, have invented certain new and useful Improvements in Car-Fenders, of which the following is a specification.

This invention relates to fender devices employed upon railway cars, street cars, trolley cars, and the like, and has for one of 10 its objects to simplify and improve the construction and increase the efficiency and utility of devices of this character.

Another object of the invention is to provide 15 a device of this character that will follow the track when the car is traveling on curves and around street corners.

Another object of the invention is to provide 20 a device of this character which may be readily adapted without material structural change to cars of various forms and sizes.

With these and other objects in view, the 25 invention consists in certain novel features of construction as hereinafter shown and described and then specifically pointed out in the claims, and in the drawings illustrative of the preferred embodiment of the invention.

30 Figure 1 is a side elevation of a portion of a conventional street car with the improved fender applied, and partly in section.

Fig. 2 is a plan view of the improved 35 fender, detached.

The improved fender comprises a supporting frame 10 preferably of metal of suitable strength and converging at the rear into a single rod 11, the latter having a ball 12 at 40 its rear end.

The frame 10 is formed with spaced sides in parallel relation and with a forward portion at right angles to the sides, the forward portions of the frame sides being bent 45 downwardly as at 13 to bring the forward ends relatively near the tracks, represented at 14.

Supported from the side members of the frame 10 is a transverse frame 15 having 50 downturned ends terminating in bearings 16 to carry flanged track engaging wheels 17, the bearings having suitable oil reservoirs, indicated at 16'.

Attached to the frame 10 is a plurality of 55 metal strips or ribs, 18, extending longitudinally of the frame and constituting the plat-

form or face of the fender, the ribs following the contour of the frame 10.

Rising from the wheel carrying frame 15 is a tubular standard 19, and slidably in the standard is a pin or plunger 20, the latter carrying an antifriction wheel or roller 21 in its upper end adapted to engage a curved bearing plate 22 attached to the under face of the car body, a portion of the latter being 65 represented at 23. The pin 20 is held from rotation in the standard by a pin 20' and slot 20².

A spring 24 is disposed within the standard 19 and bears beneath the plunger 20 and 70 maintains the wheel 21 yieldably in engagement with the bearing plate 22.

Attached to the car body 23 rearwardly of its forward end, is a bracket device formed of coacting members 25 and 26. The bracket 75 member 25 is adapted to be bolted or otherwise attached to the car body 23, while bracket member 26 is bolted or otherwise attached to the member 25. The members 25 and 26 are formed with coacting half bearings 80 to engage the ball 12 on the frame member 11. The bearings for the ball 12 are beveled outwardly as shown at 27 and 28, so that the fender frame and its attachment and the car body 23 will have free play relative 85 to each other.

By this means the fender device is flexibly coupled to the car and will readily adapt itself to changes in grade, and the curvatures of the track, without cramping. 90

One of the improved fender devices may be attached to the rear of the car, if required, to become effective when the car is moving rearwardly.

The coacting members 19 and 20 with the 95 wheel or roller 21 and spring 24, serve as shock absorbers to prevent the car from rocking abnormally.

The preferred embodiment of the invention is disclosed in the drawings and set 100 forth in the specification, but it will be understood that any modifications within the scope of the claims may be made in the construction, without departing from the principle of the invention or sacrificing any of 105 its advantages.

What I claim is:

1. An apparatus of the class described comprising a frame including spaced side members inclined upwardly and rearwardly 110 converging to the rear and adapted to be swingingly attached at the converging por-

tion to a car body, track engaging wheels connected to said frame, a plurality of continuous slats connected to said frame and extending longitudinally thereof, a standard carrying a bearing wheel adapted to engage the under face of the car body, and means for yieldably supporting said standard from the frame.

2. In an apparatus of the class described,
10 a bracket device adapted to be attached to
a car body, a fender swingingly coupled to

said bracket, track engaging wheels connected to said fender, a tubular standard supported by said fender, a plunger operating in said tubular standard and carrying a bearing wheel adapted to engage the under face of the car body, and means for yieldably supporting said plunger in said standard.

In testimony whereof, I affix my signature hereto.

CARL O. FIRST.
